UNITED STATES PATENT OFFICE.

WILLIAM BURDETTE SNOW AND FRANK D. SHAFFER, OF PORTLAND, OREGON.

DEVICE FOR LOCKING GAME-BALLS ON A TABLE.

1,174,190.

Specification of Letters Patent.

Patented Mar. 7, 1916.

Application filed May 11, 1915. Serial No. 27,454.

To all whom it may concern:

Be it known that we, WILLIAM BURDETTE SNOW and FRANK D. SHAFFER, citizens of the United States, and residents of Portland, county of Multnomah, and State of Oregon, have invented a certain new and useful Improvement in Devices for Locking Game-Balls on a Table, of which the following is a specification.

Our invention has for its purpose the providing of a device to be used in connection with a pool table, or other game table, by means of which the set of game balls may be locked or irremovably secured on the table, so as to prevent them from being tampered with or stolen.

Incidentally our invention also has for its purpose the making of these locking means of simple form and so that they may be readily applied and fastened on any pool or other game table without drilling any holes or otherwise mutilating the table.

The construction and application of our device will be readily understood by having reference to the accompanying drawings, in which—

Fig. 1 is a plan view showing our device in actual use; Fig. 2 is a front elevation of the same showing the face of the retaining case removed; Fig. 3 is a cross-section looking toward the right, on the line indicated by the arrow A in Fig. 2.

Referring now to these drawings, *a* represents the top of a pool table.

b—*b* are the cushions and *c*—*c* are the side rails.

d is a corner pocket.

It will be noticed by having reference to Figs. 1 and 2, that the side rails *c*, *c* are each provided with a beaded edge *e*.

f represents the numbered balls of a pool set and *g* is the cue-ball.

h is the triangle by means of which the balls are racked up.

In the drawings, the set of balls is shown in racked up position, in which they are normally arranged whenever the table is not in use.

The parts which comprise our invention are as follows: *i* is a bottomless case of substantially triangular form adapted to be placed over the triangle *h*, and the balls racked therein. In the top of the case *i* is a hole *j*, and straps *k* are riveted over said hole. When the case is placed down over the entire set of balls, the cue ball *g* will be

securely inclosed in the spherical pocket formed by the straps *k*. An angle bar *m* is riveted to the top of the case *i*, and said angle bar is provided with a perforation *n*. 60 An angle bar *o*, has its ends *p* bent in hook-shaped form, and curved so as to conform to the table when such parts come in contact. The flange of the angle bar *o* is provided on its front face with an angular lug *r*, and the lower face of the bar *o* is provided with a felt strip *q*, or other soft body surface, which serves to prevent said bar *o* from scratching or otherwise marring the rails of the table when such parts come in contact. The 65 flange of the bar *o* is provided with a perforation *s*. When the angle bar *o* is placed on the case *i*, the lug *r* serves as a templet for bringing the holes *s* and *n* in registration with each other. A latch bar *t* is pivoted to the flange of the angle bar *o*, said latch being approximately of U-shaped cross-section, as shown in Fig. 3, and adapted to engage the flanges of both angle bars *m* and *o*. The latch bar *t* is made with a 70 finger piece *u*, and holes *v*, the latter being located so as to register with the holes *n* and *s*. See Fig. 3. A lock *w*, of standard type, is adapted to have its shackle inserted through the registering holes *n*, *s* and *v*; so 75 that when it is in such inserted position, the parts will be locked in the position shown in Fig. 2.

The application of this device to use on the regulation pool table is shown fully in Fig. 1, and is as follows: The case *i* is placed over the rack of balls and the whole combination is moved over to a corner of the table so that one corner of the case projects into the corner pocket *d*. The angle bar *o* 80 is then placed in position, as shown in Fig. 1, so that its ends will engage the side rails of the table. When the parts have been brought to their related positions, as shown in Fig. 1, the latch bar *t* is thrust down so 85 as to engage the angle members *m* and *o*. The lock *w* is then applied in the manner previously explained. The set of balls will thus be immovably locked on the table, and will be proof against any tampering or use 90 until the lock *w* has been removed.

We claim:

1. A bottomless case adapted to be placed over a group of balls on a table and arranged so as to engage a corner of the table top, a 95 bar provided with means for being engaged to the table when arranged at a top corner

- of the latter, and lock-controlled means connecting said bar and case, when these members are in engagement with the table and adapted to immovably secure said parts 5 against movement on the table.
2. A bottomless case adapted to be placed over a group of balls on a table and arranged so as to engage a corner of the table top, a bar provided with a perpendicular flange 10 and means for being engaged to the table when arranged at a top corner of the latter, a companion flange provided on the top of the case, the flange of said table engaging bar and said companion flange being provided with perforations for receiving the shackle of a lock when the bar and case are in engagement with the table.
3. A bottomless case adapted to be placed over a group of balls on a table and arranged 20 so as to engage a corner of the table top, a bar provided with a perpendicular flange and means for being engaged to the table when arranged at a top corner of the latter, a companion flange provided on the top of the case, and a lock-controllable U-shaped latch bar pivoted on one of said flanges and adapted to engage the other flange when the bar and case are in engagement with the table.
- 25 4. A bottomless case adapted to be placed over a group of balls on a table and arranged so as to engage a corner of the table top, a bar provided with a perpendicular flange and means for being engaged to the table when arranged at a top corner of the latter, a companion flange provided on the top of the case, a perforated U-shaped latch bar pivoted on the flange of said table, said latch bar, and said companion flange being provided with perforations for receiving the shackle of a lock when the bar and case are in engagement with the table.
- 30 5. A bottomless case adapted to be placed over a group of balls on a table and arranged so as to engage a corner of the table top, a bar provided with a perpendicular flange and means for being engaged to the table when arranged at a top corner of the latter, a companion flange provided on the top of the case, a laterally projecting lug on the bar arranged for bearing on the top of the case when the bar and case are in engagement with the table, and a lock-controllable U-shaped latch bar pivoted on one of said flanges.
- 35 6. A bottomless case adapted to be placed over a group of balls on a table and arranged so as to engage a corner of the table top, a bar provided with a perpendicular flange and means for being engaged to the table when arranged at a top corner of the latter,
- 40 a companion flange provided on the top of the case, a laterally projecting lug on the bar arranged for bearing on the top of the case when the bar and case are in engagement with the table, and a lock-controllable U-shaped latch bar pivoted on one of said flanges.
- 45 7. A bottomless case adapted to be placed over a group of balls on a table and arranged so as to engage a corner of the table top, a bar provided with a perpendicular flange and means for being engaged to the table when arranged at a top corner of the latter,
- 50 a companion flange provided on the top of the case, a laterally projecting lug on the bar arranged for bearing on the top of the case when the bar and case are in engagement with the table, and a lock-controllable U-shaped latch bar pivoted on one of said flanges.
- 55 8. A bottomless case adapted to be placed over a group of balls on a table and arranged so as to engage a corner of the table top, a bar provided with a perpendicular flange and means for being engaged to the table when arranged at a top corner of the latter,
- 60 a companion flange provided on the top of the case, a laterally projecting lug on the bar arranged for bearing on the top of the case when the bar and case are in engagement with the table, and a lock-controllable U-shaped latch bar pivoted on one of said flanges.

65 a companion flange provided on the top of the case, a laterally projecting lug on the bar arranged for bearing on the top of the case when the bar and case are in engagement with the table, a perforated U-shaped latch bar pivoted on one of said flanges, the flange of said table engaging bar, said latch bar and said companion flange being provided with perforations for receiving the shackle of a lock and adapted to register when the bar and case are in engagement with the table.

7. A bottomless case adapted to be placed over a group of balls on a table and arranged 75 so as to engage a corner of the table top, a bar provided with table engaging means at its ends adapted when in engagement with the table to position the bar across a corner of the table top, and lock-controlled means 80 on the case when these parts are in engagement with the table connecting said bar and case and adapted to immovably secure the case to the table.

8. A bottomless case adapted to be placed 85 over a group of balls on a table and arranged so as to engage a corner of the table top, a bar provided with table engaging means said table engaging means adapted to prevent lateral or longitudinal movement of the 90 bar when the latter is locked in engagement with the case, and means for locking the bar and case together.

9. A bottomless case adapted to be placed 95 over a group of balls on a table and arranged so as to engage a corner of the table top, a bar provided with table engaging means at its ends adapted to engage the adjacent sides of the table and thus position the bar across a corner of the table top, such bar provided 100 with a flange, a companion flange provided on the top of the case, and a lock-controllable U-shaped latch bar pivoted on one of said flanges.

10. A bottomless case adapted to be placed 105 over a group of balls on a table and arranged so as to engage a corner of the table top, a bar provided with table engaging means at its ends adapted to engage the adjacent sides of the table and thus position the bar across 110 a corner of the table top, such bar provided with a flange, a companion flange provided on the top of the case, a laterally projecting lug on the bar arranged for bearing on the top of the case, a perforated U-shaped latch 115 bar pivoted on one of said flanges, the flange of said table engaging bar, said latch bar and said companion flange being provided with registering perforations for receiving the shackle of a lock.

WILLIAM BURDETTE SNOW.
